CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

CIRCUIT INTERRUPTER.

Application filed February 26, 1921. Serial No. 448,272.

My invention relates to circuit interrupters and particularly to contact members employed in connection therewith.

One of the objects of my invention is the provision of a contact member of such form that it may be acted upon by the magnetic forces set up by the passage of current therethrough to be more firmly biased into contacting engagement with a co-operating contact member.

Another object of my invention is to provide, in connection with a bridging member and a pair of stationary contact members, a pair of contact members so arranged as to utilize the magnetic forces set up by the passage of current through the respective pairs of such contact members in such manner that the contact members of each pair will be biased toward their closed position, as opposed to the repellent magnetic forces present in the zone between the stationary contact members.

Still another object of the invention is the arrangement of laminations in a bridging member in such position that the opposing magnetic forces that are set up by the passage of current through the conductors will act against the edges of such laminations instead of against the sides thereof.

Circuit breakers for unusually high voltages and large currents are usually constructed in such manner that the path of current therethrough is of substantially U-shape, and the magnetic forces set up in that portion of the circuit between the legs of the U exercise a repellent force, which tends to distort the switch parts and break the circuit.

Furthermore, in bridging members that are formed of laminations, the laminations are usually arranged flatwise and have their ends upturned to make engagement with the co-operating contact members. Such arrangement results in a tendency of a laminated bridging member to become distorted by the repellent forces above referred to.

I accomplish the foregoing by constructing the bridging member of laminations arranged in edgewise relation with respect to the engaging surfaces of the stationary contact members and by dividing the laminations into angularly disposed groups adjacent their points of engagement with the stationary contact members.

As shown in the accompanying drawing:

Figure 1 is a view, in end elevation, of a portion of a circuit interrupter with my invention applied thereto, and

Fig. 2 is a similar view, in side elevation.

The circuit breaker consists of a pair of operating rods 3, a pair of conductors 4 (only one of which is shown), and a bridging member 5. A stationary contact member 6 is secured to the conductor 4 by bolts 7 and 8. The bolts 8 also serve to secure yielding supporting members 9 to the stationary contact members. A pair of arcing tips 10 are carried by the supporting members 9, while flexible shunt members 11 serve to conduct the current from the arcing tips 10 to the stationary contact member 6.

Brushes 12 and 13, comprising a plurality of laminae having their broadest faces in juxtaposition and of substantially U-shape having oppositely flaring ends, are secured to the bridging member 5 by means of bolts 14, being clamped between the castings 15 and 16. These brushes are adapted to engage the stationary contact members 6 with a resilient but firm contact by each individual lamination by reason of the flaring shape of the end portions to complete the circuit.

A pair of movable arcing tips 17 are secured to the bridging member 5 by means of bolts 18 and are adapted to co-operate with the stationary arcing tips 10 to protect the brushes 12 and 13 against arcing, in the manner common to devices of this character.

The stationary arcing tips 10 are yieldingly supported so that they may maintain engagement with the movable arcing tips 17 until after the bridging member has been moved to open position sufficiently far to eliminate danger of arcing between the brushes and the stationary contact member.

It will be understood that Fig. 2 shows but substantially one-half of a circuit breaker, the operating rods 3 being mounted midway between two sets of contact members, such as those hereinbefore described.

When the brushes 12 and 13 are angularly disposed, as shown, the magnetic force set up by the passage of current through the conductor 4 and the contact members, because of the attraction between parallel conductors carrying current in the same direction, acts to bias them toward the center line of the current and

thereby causes brushes 12 and 13 to more firmly engage the adjacent stationary contact member 6. Since the plane defined by the upper ends of the castings 15 and 16 is parallel to the face of the contact member 6, the lengths of the flexing portions of the laminæ comprising the brushes 12 and 13 are substantially equal. Accordingly, they are under equal internal stresses. In this manner, I neutralize the repellent tendency of the magnetic forces that are set up in the zone between the two legs of the circuit breaker.

The edgewise arrangement of the laminæ adds to the strength of the device, as compared to the flatwise arrangement heretofore employed.

The brush members need not necessarily be carried on the movable contact, or bridging, member but may be mounted on the stationary contact member. It will further be understood that I do not limit myself to a laminated bridging construction, but that other forms of yielding contact members may be employed. Furthermore, the angularly-disposed arrangement of contact members may be advantageously employed in circuit interrupters provided with a single-break instead of the double-break arrangement just described.

Various other modifications may be made without departing from the spirit and scope

of the invention as defined in the accompanying claims.

I claim as my invention:—

1. The combination with a contact member, of a relatively movable brush member comprising a plurality of laminæ arranged in edgewise relation to the face of the contact member and clamping means for the laminæ disposed at a distance from the ends of the laminæ, the portions of the laminæ beyond the clamping means being divided into oppositely flared groups whereby the lengths of the flexible portions of the individual laminæ are substantially equal.

2. The combination with a contact member, of a relatively movable brush member comprising a plurality of laminæ arranged in edgewise relation to the face of the contact member and clamping means for the laminæ disposed at a distance from the ends of the laminæ, the portions of the laminæ beyond the clamping means being divided into oppositely flared groups whereby the lengths of the flexible portions of the laminæ inherently exert substantially the same pressure upon the contact member.

In testimony whereof, I have hereunto subscribed my name this 17th day of February 1921.

CHRISTIAN AALBORG.
